United States Patent Office.

SAMUEL GLASSON, OF NEW YORK, N. Y.

Letters Patent No. 82,618, dated September 29, 1868.

IMPROVED REAMER AND TAP.

The Schedule referred to in these Letters Patent and making part of the same.

TO ALL WHOM IT MAY CONCERN:

Be it known that I, SAMUEL GLASSON, of the city, county, and State of New York, have invented a new and useful Improvement in Expanding-Reamers and Taps; and I do hereby declare that the following is a full, clear, and exact description of the same, reference being had to the accompanying drawings, forming a part of this specification, in which—

Figure 1 represents a longitudinal section of a reamer or tap constructed according to my improvement, and Figure 2 a cross-section of the same.

Similar letters of reference indicate corresponding parts in both figures.

This invention consists in the construction of a reamer or tap with a hollow cylindrical stock, carrying within its central cavity a plug, which is operated by a screw, and which is provided with inclined grooves, in which are received the backs of cutters projecting from slots in the stock, the said cutters being adjustable by the longitudinal movement of the central plug, produced by the turning of the screw, aided by springs arranged within the stock.

In order that others may be better enabled to understand the construction and operation of my invention, I will proceed to describe it with reference to the drawings.

A is the stock of the reamer or tap, of a cylindrical form, provided in its sides with longitudinal slots, which communicate with a central bore, *a*, extending lengthwise of the stock, nearly the entire length thereof. Within these slots are fitted cutters *B*, which are provided with springs *s s s s*, secured in the ends thereof, and so acting against the inner surface of the stock as to retain the said cutters within their slots.

Within the central cavity of the stock is fitted to slide a plug, *C*, of cylindrical form, but having longitudinal tapering or inclined grooves *c* cut upon it, said grooves tapering inwardly, or sinking deeper into the plug at the inner than at the outer extremity. Fitted within the outer end of this plug *C*, is a screw, *e*, which passes through and has its bearing within a block, *E*, secured within the open end of the stock *A*, and its outer end terminating in a square head, whereby the stock is turned. This screw *e*, passing through the said block *E*, terminates in square head *f*, beyond the outer end of the bearing-block *E*. That part of the screw *e*, within the said bearing-block *E*, is not threaded, but plain, so as to allow the said screw a rotating, without a longitudinal motion therein; forward and backward motion being prevented by shoulders *f* and *g* upon the said screw *e*, at each end of the block *E*. The said bearing-block *E* is prevented from turning in the stock *A* by a set-screw, *h*, passing through the thickness or shell of the stock, and entering the said block *E* a sufficient depth to effect the purpose for which it is designed, or the entrance of the central opening *a* may be tapped, and a thread cut upon the inner end of the block *E*, and thereby establish the desired connection.

By turning the screw *e* backwards, the plug *C* is forced deeper into the cavity of the stock, exerting a wedge-like action against the cutters, by means of the tapering grooves acting against the backs thereof, which are also provided with an inclined or tapering form, to fit the tapering inclination of the said grooves, thereby causing a yielding of the springs *e*, and projection of the cutters beyond the periphery of the stock *A*. By turning the said screw forward, the plug *C* is drawn backward, relieving the pressure of the grooves against the cutters, which are simultaneously drawn inward by the springs *e*. By providing the edge of the cutters with suitable teeth or corrugations, this invention is made applicable to taps for cutting threads, and for various other purposes.

What I claim as my invention, and desire to have secured by Letters Patent, is—

The arrangement, herein described and shown, of the tubular stock *A*; grooved plug *C*, cutters *B*, springs *s*, and swivelled screw *E e*, for the purpose set forth.

SAMUEL GLASSON.
